INVENTOR:

Fred H. Loveless,
By Frank H. Koenig
ATTORNEY.

UNITED STATES PATENT OFFICE.

FRED H. LOVELESS, OF CHICAGO, ILLINOIS, ASSIGNOR OF TWO-THIRDS TO JAMES ROWAN AND WILLIAM M. HASTEY, BOTH OF MARION, INDIANA.

COMBINED SIGN AND BULLETIN BOARD.

1,308,502.

Specification of Letters Patent.

Patented July 1, 1919.

Application filed August 24, 1918. Serial No. 251,334.

To all whom it may concern:

Be it known that I, FRED H. LOVELESS, a citizen of the United States, residing at Chicago, in the county of Cook and State of Illinois, have invented certain new and useful Improvements in Combined Sign and Bulletin Board, of which the following is a specification.

This invention relates to a combined sign and daily bulletin board; and one of the objects of the invention consists in the provision of a combined sign and bulletin board of the above character whereby the privilege for locating and maintaining the boards can be paid for by the allotment of certain bulletin display space, so that the lessee can display from day to day such produce as he has for sale and also the commodities he desires to buy, and thereby avoid annoyances and loss of time on part of both the buyer and seller in promoting and carrying out merchantable transactions, besides facilitating the extension and maintenance of the display of permanent advertising matter. A further object of the invention consists in the provision of a combined advertising display sign and daily bulletin board which is simple in construction and cheap to manufacture. I accomplish the above objects of the invention, and such others as may appear from a perusal of the following specification and claims, by means of the construction illustrated in the accompanying drawings, forming a part hereof, in which—

Figure 1 is a perspective view of my improved advertising display sign and bulletin board. Fig. 2 is a vertical sectional view through the board. Fig. 3 is a fragmentary detail vertical sectional view, on an enlarged scale, of the board. Fig. 4 is a fragmentary detail vertical sectional view of a modified form of construction of my improved sign and bulletin board.

Referring to the drawings, 10 and 11 represent a pair of parallel upright members which form the sides of the sign-frame, and the members 10 and 11 may extend sufficiently below the display board as to form posts to be let into the ground for holding the sign board erect without additional bracing. The upper ends of the members 10 and 11 are connected by means of a top-rail 12 forming the upper member of the sign-frame, and the lower portions of members

10 and 11 are connected together by means of a tie-rail 15. Members 10 and 11, and the top-rail 12 are usually provided with a centrally located and longitudinally extending groove or kerf 16. The continuous channel formed by groove 16 in the members 10 and 11 and top-rail 12 forms a seat for the reception of the bulletin board 18 which is arranged in the upper portion of the sign-frame, and bulletin board 18 is preferably formed of sheet metal. As noted the bulletin display surface of the board 18 may be divided, as at 19, and the areas of the respective divided portions of said board may be suitably and permanently designated as "for sale" and "wanted". The space immediately below the permanent for sale sign on bulletin board 18 may be utilized by the lessee of the sign privilege for the purpose of displaying such produce as he may have for sale at that time to the huckster and the passers-by, and on that portion of the board 18 immediately below the permanent sign wanted he can display such commodities as he desires to buy, so that anyone desiring to purchase any of the commodities displayed for sale will not be embarrassed by making inquiries, and relates equally to those who have commodities for sale. The articles designated for sale or the commodities desired to be purchased which are displayed on the daily bulletin board 18 will usually be written in by chalk so as to enable the same to be readily removed when it is desired to change the wording of the bulletin. As chalk is not permanent in character, it may be readily removed either manually or by rain. Therefore, in order to prevent the permanent portion of the display board 25 from being streaked and marred by the chalk water draining down from bulletin board 18, I provide an inclined water-table 26 along the upper edge of board 25 so that as water discharges from the lower edge of bulletin board 18 it strikes the inclined surface of water-table 26 and is conveyed thereby rearwardly and back of board 25. As the permanent board 25 is usually made of sheet metal, water-table 26 may easily be bent out of the metal sheet extending along the marginal edge of board 25, and the free edge of water-table 26 may be strengthened or reinforced by adding a bead 27 which may be formed by bending the metal edge back against the

surface of the water-table, as clearly shown in Fig. 3 of the drawing. The ends of the bent portion of water-table 26 will usually be bent downwardly to form the depending 5 ears 28 and serve to anchor the upper portion of board 25 to the adjacent sides of upright members 10 and 11, by means of suitable nails 29. The lower edge of board 25 is usually nailed fast to the outer face 10 of tie-rail 15 so that such water as may be driven against the front surface of board 25 will readily be drained away.

Bulletin board 18 and sign board 25 are separated a sufficient distance apart to provide 15 an intervening air gap 23 for the passage of air therethrough and thus greatly relieve sign structure of wind pressure normally exerted against a tight sign board of correspondingly exposed surface area.

20 In Fig. 4 of the drawings I have shown rail 15 extending forwardly to the front edges of side members 10 and 11, and in this instance tie-rail 15 is also provided with a kerf 16 to receive the lower edge of board 25, and the forward upper surface of tie-rail 15 in advance of board 25 is beveled, as shown, so as to freely carry away the water as it is discharged from the face of board 25.

30 Having thus fully described my said invention, what I desire to secure by Letters Patent, is—

1. A combined sign and bulletin board comprising a frame, a sign board composed 35 of two or more sections with an air gap between the edges of the sections, and a water-table arranged along the upper edge of the lower section for protecting the latter against the water drained from the upper 40 section of the sign board.

2. A combined sign and bulletin board comprising a frame, a sign board composed of two display sections with an air gap between their adjacent edges, and an inclined 45 water-table arranged along the upper edge of the lower section for catching and dis-

charging the water drained from the upper section back of the sign board.

3. A combined sign and bulletin board comprising a frame, a sign board composed 50 of two display sections with an air gap between their adjacent edges, an inclined water-table arranged along the upper edge of the lower section for catching and discharging the water drained from the upper 55 section back of the sign board, and ears formed of the ends of the water-table, and means for securing the ears to the sign frame.

4. A combined sign and bulletin board 60 comprising a frame, a sign board composed of two sections with an air gap between their adjacent edges, and an inclined water-table arranged in the air gap for conveying the water discharged from the upper sign 65 section away from the lower sign section.

5. A combined sign and bulletin board comprising a frame, a sign board composed of two sections with an air gap between their adjacent edges, an inclined water-table 70 arranged in the air gap for conveying the water discharged from the upper sign section away from the lower sign section, and means for reinforcing the free edge of the water-table.

6. A combined sign and bulletin board comprising a frame composed of a plurality of connected sections having communicating kerfs, a display board composed of a plurality of disconnected sections arranged 80 with a channel formed by said kerfs, and a water-table arranged in the space between the opposed edges of the sign sections, for conveying away the water draining from the upper sections from the lower sign sections.

In witness whereof, I have hereunto set my hand and seal at Indianapolis, Indiana, this 14th day of August, A. D. one thousand nine hundred and eighteen.

FRED H. LOVELESS. [L. S.]
